INVENTOR

Charles D. Cutts,
By his Atty
Henry Williams

UNITED STATES PATENT OFFICE.

CHARLES D. CUTTS, OF FORT FAIRFIELD, MAINE.

BIT-BRACE AND HAND-DRILL.

SPECIFICATION forming part of Letters Patent No. 538,323, dated April 30, 1895.

Application filed February 25, 1895. Serial No. 539,525. (No model.)

To all whom it may concern:

Be it known that I, CHARLES D. CUTTS, a citizen of the United States, residing at Fort Fairfield, in the county of Aroostook and State 5 of Maine, have invented a new and Improved Bit-Brace and Hand-Drill Combined, of which the following is a specification.

This invention relates to a bit-brace and hand-drill combined; and consists in a novel 10 construction and arrangement of parts whereby, principally by the employment of a removable clamp or yoke, the device may be used without the yoke or clamp as a bit-brace, or with the yoke or clamp as a drill, as herein- 15 after described and illustrated in the accompanying drawings, in which—

Figure 1 is a plan view of my improved device in position for use as a drill. Fig. 2 is a sectional view taken on line *x*, Fig. 1. Fig. 3 20 is a sectional view taken on line *y*, Fig. 1.

Similar letters of reference indicate corresponding parts.

A represents the stock or handle provided with the usual button *a*, ratchet head *B*, and 25 ratchet wheel and pawls *C*, all constructed as usual.

D is a chuck constructed to receive and hold either a bit or drill, by means of suitable jaws *D'*. The upper end of the chuck screws upon 30 the bifurcated screw *d* into which is fitted and securely fastened the shaft *E* which extends to the ratchet head and is rotated by the stock. Fitting loosely upon this shaft is a sleeve *F* externally screw-threaded and provided at its upper end with the integral hand wheel or finger wheel *H*. A suitable washer *e* lies on the shaft *E* between the sleeve *F* and the screw *d*.

K is a nut running on the thread on the 35 sleeve *F*.

L P are two curved jaws having their extensions *L' P'* hinged together at *l* and having their opposite extensions *L'' P''* adapted to be secured together by a hand screw *m*. The 40 portion *L''* of the jaw *L* is shorter than the portion *P''* of the jaw *P*, and said portion *P''* is bent up at *P'''* so as to leave a space between said portion *P'''* and the portion *L''*, and the inner ends of said portions *P'''* and 45 *L''* are beveled at *n* (as shown in Fig. 1) so as to catch and hold the links at the free end of a chain, as *R*, whose other end is secured at 50

R' at the pivotal point *l*. These jaws constitute a yoke, and their inner surfaces are hollowed out into the shape indicated in Fig. 2 55 and by broken lines in Fig. 3, such shape fitting the nut, which in this instance has six faces, and has on its opposite sides small annular shoulders *K'* upon which the inner edges of the shells which constitute the jaws *P L* 60 of the yoke rest.

When the device is to be used as a bit, neither the yoke *P L* nor the chain *R* is used, both being removed. Moreover the nut *K*, the hand wheel *H* and the threaded surface of the 65 sleeve *F* are not in use. The stock is simply rotated, and the shaft *E* rotates the chuck and bit in the usual manner; but when the device is to be used as a drill as indicated in the drawings, in which it is represented as 70 drilling a hole in a metal pipe *S*, the yoke *L P* is secured in position on the nut *K* by means of the hand screw *m*, and the drill is held up to its work by the chain *R* which is made taut by catching it between the outer end of the 75 jaw *L* and the inner surface of the portion *P'''* of the jaw *P*. Now as the device is held in the ordinary position, which is usually with the button pressed by the body of the user, as the stock *A* is rotated, with the effect of 80 driving the drill into the metal, the threaded sleeve *F* remains stationary, as does also the yoke *P L* and consequently the nut *K'*. The effect of this is of course to slacken the chain *R* as the drill enters the metal. In order to 85 prevent this slackening of the chain the hand wheel *H* is turned by the thumb or finger of the operator, thus rotating the sleeve *F* just enough to cause the nut *K* and consequently the yoke *P L* to travel back on said threaded 90 sleeve sufficiently to keep the chain taut. By reversing the movement of the hand wheel or feed wheel *H* the chain *R* will be loosened and can be disconnected.

Thus it will be seen not only that the device 95 is adapted for use both as a drill and bit, but also that when it is to be used as a bit the yoke and chain being removable, are out of the way and do not serve to encumber the tool.

Having thus fully described my invention, 100 what I claim, and desire to secure by Letters Patent, is—

In a bit-brace and hand-drill combined, the combination with the stock, chuck, shaft *E*,

sleeve F on said shaft and externally screw-threaded, hand wheel or feed wheel H rigid with said sleeve and nut K running on said threaded sleeve, of the removable yoke consisting of a pair of jaws pivoted together at one end and adapted to be secured together at the other end, said jaws being adapted to clamp the nut and prevent movement thereof

with relation to the yoke, and said yoke being adapted to receive the opposite ends of the chain which is passed around the work, substantially as set forth.

CHARLES D. CUTTS.
